UNITED STATES PATENT OFFICE.

ARTHUR WILLIAM MCCOMAS AND HENRY ALEXANDER FITZHUGH, OF AUSTIN, TEXAS.

FAN FOR ROCKING FURNITURE.

SPECIFICATION forming part of Letters Patent No. 408,188, dated July 30, 1889.

Application filed November 4, 1887. Serial No. 254,276. (No model.)

To all whom it may concern.

Be it known that we, ARTHUR WILLIAM MCCOMAS and HENRY ALEXANDER FITZHUGH, citizens of the United States, residing at Austin, in the county of Travis and State of Texas, have invented certain new and useful Improvements in Fans for Rocking Furniture; and we do hereby declare the following to be a full, clear, and exact description of the invention, such as will enable others skilled in the art to which it appertains to make and use the same.

Our present invention is an improvement in fans for rocking furniture and a supporting-frame arranged for two co-operating fans.

In our patent, No. 336,128, we employed a single plain fan suspended from the ends of outreaching arms of a fan-holding frame, which in practice we find answers a very good purpose, and now we come before the Patent Office with what we consider an improvement upon said patent having but one fan, and employ here two, to be operated from the same movement, or either one of the two. One of these fans agitates the air in front of a seated person, and the other, being suspended above the head, agitates the air back and above, and as both fans may be operated together we effect action and reaction to the air, and thus give it a freshness and invigorating quality very desirable in a very hot climate. The overhead fan has a frame composed of two straight horizontal rods and one curved rod secured to two vertical rods. The angles at the intersecting points of the horizontal and vertical rods are right angles. The fan proper of this frame includes the middle horizontal bar, the bottom curved bar, and the covering fabric for the same, and the form of said fan is quite like the blower of a fire-grate, and it has an area considerably less than that of the forward fan. The fan-supporting frame is composed of two graduated upright standards connected at their upper ends by a horizontal bar and adapted at their lower ends to telescope in sleeves having thumb-screws, by which said standards are held to given positions. From clevises or clips secured to the tops of the said standards extend outreaching rods or arms, and between clevises fixed cen-

trally on said rods is secured a rod which braces said arms. The standards of the fan-supporting frame have collars provided with clevises and set-screws, and between these and the respective outreaching arms are pivoted diagonal bracing-rod for said arms, which may be held to horizontal or other radial position. The overhead fan is suspended from loops secured to the bracing-rod for standards in a manner hereinafter to be described, so that said fan may be readily detached when one fan only is needed—i.e., the forward one. To the upper portions of the upright standards we pivot catches adapted to embrace the vertical rods of the overhead fan and hold it when the temporary suspension of the vibration of said fan is desirable. The forward one of the two fans has a rectangular skeleton frame composed of a horizontal straight bar, two vertical bars extending therefrom, and connecting these two latter is a corrugated weighted bar. Upon this skeleton is stretched a suitable fabric, which, when in place, forms the corrugated fan. The upper horizontal bar of this fan has journals, which find bearings in the ends of the outreaching arms of the fan-holding frame. The sleeves into which the upright standards of the fan-holding frame telescope are enlarged at their tops for purposes of strength, and have holes for the thumb-screws, which pass into them. At the bottoms said sleeves terminate with disks hinged to corresponding disks on short bars, which have secured to them clasps to take hold of the upright round portions of a piece of rocking furniture. The clasps, one of which we describe, are formed of two metal plates, one fixed to the short bars mentioned and provided with one portion of a hinge and a curved clasping portion. The other plate has a corresponding shape and the other portion of a hinge. By a movement of the latter-mentioned plate about its axis the jaws of the clasp are brought near each other to take hold of the round piece of the furniture. To the movable clasp-plate is pivoted a screw-threaded bolt, which passes through an opening in the fixed portion of the clasp, and by means of a nut the two said portions of the clasp are held firmly to place. The disk-

hinges which connect the short clasp holding-bars and the sleeves for the standards are not unlike those in our application Serial No. 221,399, and need not be particularly described in this application.

In our drawings, Figure 1 is a side elevation showing the fan-holding frame, fans, &c. Fig. 2 is a rear or back view of the same. Figs. 3, 4, and 5 are detail drawings of the clamping device and adjustable bearing-loop for the back fan.

Similar reference-letters indicate like parts in all of the figures.

Referring to the drawings, A A are the upper standards for the fan-holding frame provided with annular graduated marks.

B B are the sleeves into which said standards telescope.

a are the thumb-screws for holding the standards with reference to the sleeves B.

C are the short bars, to which are fixed the clasping devices E E'. These short bars have at their upper ends disks D, which, together with corresponding disks D' on the sleeves B, form hinge-joints, by which the rake or inclination of the chair or piece of rocking furniture and the angle of the standards of the fan-holding frame may be made conformable.

E E are the clasping-plates secured to and forming parts of the short bars C. E' are the corresponding clasping-plates hinged to the fixed portions E. The plates E E' are hinged together with the pin n² and clamped together by means of the screw n³ and nut n⁴.

F are outreaching arms pivoted in clevises b at the upper ends of the standards A A.

G is a bar connecting the ends of the standards, and H is a bar connecting the two outer ends of the outreaching arms.

I are diagonal bracing-bars connecting the arms F by clevises c², and the upright standards A A by the combined clevises or clips e and sleeves c.

f are the thumb-screws, which hold, through the bracing-bars I, the outreaching arms F to suitable position.

J is a rod which connects and braces the arms F.

K is a horizontal curved bar, L a straight horizontal bar, and M M vertical bars connected by a bar N, all forming the overhead fan-frame, and O the covering fabric of said fan.

The bar N extends outside of the vertical bars M M, forming journals which rest in bearing-loops P P', secured to the bar G of the supporting-frame. Loop P is adjustably secured to the bar G by a thumb-screw r, and the loop P' is riveted to said bar G.

Q are forks pivoted to the standards A A, which may be made to engage the vertical bars of the back fan to hold it quiet with reference to the fan-holding frame while the rocking-chair is in motion.

R is the front fan, formed of a suitable skeleton frame which has a horizontal straight bar H, journaled in arms F, and a lower corrugated or zigzag bar m⁶. When said frame is covered with a suitable fabric, a corrugated fixed fan is formed, as previously described.

The front fan hinged to the ends of the horizontal bar H, when not required as a fan, may be turned back, so as to rest upon the horizontal portion of the fan-holding frame, as shown in Figs. 1 and 2 of the drawings, and serves in this position as a canopy to protect the occupant of the chair from the rays of the sun.

It is sometimes desirable that the back fan be for a time dispensed with, and under such circumstances it is only necessary to loosen the screw r in the loop P from the bar G, in order that the fan L M N O R may be detached from the fan-holding frame.

Having thus described our invention, what we claim as new, and desire to secure by Letters Patent, is—

1. The combination, with the fan-supporting frame having a bar G, with one fixed loop and a corresponding loop secured by a thumb-screw, of the back fan and its frame journaled in said loops, as set forth.

2. The combination, with the fan-supporting frame, substantially as described, the fan O, adjustably journaled to the bar G, and the holding-forks Q, pivoted to uprights A, of the fan R, pivoted to the ends of the horizontal arms of the frame, all arranged to form a set of fans for front and rear service, as set forth.

In testimony whereof we affix our signatures in presence of two witnesses:

ARTHUR WILLIAM MCCOMAS.
HENRY ALEXANDER FITZHUGH.
